TRUSS

Jim M. Bass, Lufkin, Tex.

Application January 4, 1940, Serial No. 312,420

1 Claim. (Cl. 128—105)

This invention relates to a truss.

It is aimed to provide a truss which will cling to the body and remain in place even while the wearer works, and one which is of minimum bulk so that the wearing thereof cannot be detected through bulging or the effect on the clothing.

I especially aim to provide such a construction as will positively stay in the position where it is placed, a construction which is of minimum weight, one which will not scald, rub or blister the skin of the wearer, avoids springs around the small of the back or other means which is the cause of backache and kidney trouble, and a construction which will enable free circulation and movement of the back without displacing the spring or the springs or pads. I also avoid leg straps or strong heavy springs. The construction may be worn at all times.

The more specific objects and advantages will become apparent from a consideration of the description following taken in connection with accompanying drawing illustrating an operative embodiment.

In said drawing:

Figure 1 is a perspective view of the truss; Figure 2 is an enlarged view showing one of the pads in elevation and adjacent parts in section;

Figure 3 is a section taken on the line 3—3 of Figure 2;

Figure 4 is a cross section taken on the line 4—4 of Figure 2;

Figure 5 is an elevation looking toward the back; and

Figure 6 is a detail perspective view illustrating a modified form.

Referring specifically to the drawing wherein like reference characters indicate like or similar parts, 10 designates a strap of leather or the equivalent adapted for disposition across the back of the wearer which preferably has enlarged terminals or end portions 11. Longitudinally extending loops 12 are stitched as at 13 to the enlarged portions 11 and buckles 14 are carried by short straps 15, fastened to the portion 10 adjacent the loops 12.

Pads are shown at 16 having clamp plates 17 and 18 secured by bolts 19 to leather backing members 20 having a soft outer lining 21, to engage the skin directly and which may for instance be of buckskin. A cushioning disk or body 22 is disposed within the lining and against the backing members 20, the same being sponge rubber or any equivalent.

The clamping plates 17 and 18 under any desired pressure, according to the adjustment of the

screws 19, engage inclined terminals 23 of generally arcuate metallic spring wires 24, which terminate at their inner ends in eyelets 25 which are normally housed within the loops 12. Said wires 24 are preferably covered by a narrow relatively flat tubular band 26 of leather or the like and a short strap of leather 27, is connected to each eyelet 25 and is adjustably engageable at holes 28 in such straps 27 with the tongues 29 of the buckles.

A leather or other strap 30, which is relatively narrow like that at 26, is provided in adjustable sections 31 and 32 having terminal loops 33 and 34 respectively engaged with the angular terminals 23 of the spring wires 24. Section 31 carries a buckle 35 and a loop 36. The section 32 has a series of holes 37 selectively engageable by the tongue 38 of the buckle and insertable through the loop 36.

Attention is called to the fact that the straps 26 and 30 are usually about three-eighths of an inch or one-half of an inch wide. The entire device weighs but a few ounces. The truss is placed around the body at the small of the back and the spring wires 29 and enclosing parts fit around the hips about two inches below the top of the hip bone. The structure may be worn day and night with comfort. This is true even when the wearer is at work. The structure may be adjusted at the front so that it will fit the rupture 30 and will give the pressure required. I find that the structure will positively cling to the body and remain in its proper position at all times. Attention is called to the fact that the pads 16 are relatively small and very thin whereby they fit so closely to the body that they are completely out of the way. The device does not produce bulk and its presence cannot be detected through the clothing. Free circulation and movement of the back is assured.

Various changes may be resorted to provided they fall within the spirit and scope of the invention. For instance as shown in Figure 6, a form is provided wherein a single spring truss may be made out of the double spring truss described with respect to Figures 1 to 5. In such form a strap 10' is provided in lieu of that at 10 constructed at one end like that at 10 and having therefore a buckle 14' functioning like the buckle 14 and also having a loop 12' like that at 12. One of the spring wires 24 at its eyelet 25 is adapted to be connected by a strap 27 to the buckle 14', such wire 24 being covered by the leather as at 26 and having the inclined terminal 23 on which a pad 16 is mounted as in the first form. At the

other end of the strap 10', in lieu of a spring and associated structure, I stitch at 39 a leather strap 40. In this form, the strap section 31 with its loop 36 and buckle 35 are also employed and the strap 40 at the openings 41, is adapted to adjustably engage with the tongue of the buckle 14'. Such a structure may be made in either right or left, according to the location of the rupture.

I claim as my invention:

- 10 A truss having a strap for disposition at the back, loops on said strap adjacent opposite ends

thereof, spring wires having eyelets, buckle means at the ends of the strap connected to the eyelets, said eyelets being housed, in said loops, straps on said wires, said wires at their forward ends having downwardly converging terminals, pads having clamps engaging said inclined terminals, and adjustable strap means having downwardly diverging portions at opposite ends secured about said terminals.

10
